ABSTRACT: The crossarm assembly is made of electrically nonconductive noncorrosive materials within an arcuate crossarm and a pair of legs for supporting the arcuate crossarm on a pole. Channel-shaped brackets are used to secure the arcuate crossarm to each leg while a dowel pin is inserted within mating recesses of the crossarm and the support legs in order to position the crossarm and to resist the loading of the crossarm.

CROSSARM ASSEMBLY

This invention relates to a crossarm assembly. More particularly, this invention relates to a crossarm assembly for electrical distribution lines.

Heretofore, various types of crossarm assemblies have been utilized, for example, for electrical distribution lines. Generally, these assemblies have been made with components formed of various types of materials such as laminated wood in order to be electrically nonconductive while being resistant to weathering. However, in many instances, the supports for supporting or securing the crosspieces to the pole have simply been made of wood. In such cases, the wood is subjected to the corrosive effects of weathering and therefore requires periodic replacement.

Further, in most cases, the crossarm assemblies have consisted of a horizontal crosspiece which is secured to a vertical pole in various manners. Because of this arrangement, the horizontal crosspieces have been designed either for left-hand or right-hand construction. That is, since the crosspieces must be secured to one or the other side of the pole with respect to the distribution lines, the securing means, such as supporting struts and bolts, must be constructed so as to secure the crosspieces to either side of the pole.

Accordingly, it is an object of this invention to provide a crossarm assembly which is mounted symmetrically on a vertical pole.

It is another object of this invention to provide a crossarm assembly which is made of noncorrosive nonconductive materials.

It is another object of this invention to provide a crossarm assembly which can be easily and quickly installed.

It is another object of this invention to provide a crossarm assembly in which a crosspiece can be easily removed from the structure supporting the crosspiece on the vertical pole.

Briefly, the invention provides a crossarm assembly including a crosspiece and a pair of support legs which support the crosspiece symmetrically above a vertical pole. The crosspiece and the support legs are made of noncorrosive nonconductive material, for example, resin impregnated glass fibers. In one instance, the crossarm is formed in an arcuate curvilinear shape and is positioned concave up with respect to the pole while in another instance the crossarm can be positioned concave down.

In order to mount the arcuate crossarm on the support legs, suitable securing means are used. For example, where the crossarm and support legs are made as solid components, a dowel pin is positioned within mating recesses within each of the crossarm and support legs while a pair of channel-shaped retaining brackets are disposed about the arcuate crossarm and are secured to the support legs. The dowel pins can be made of metallic or nonmetallic material and may be of any suitable cross section. These dowel pins assure proper positioning of the crossarm and prevent the crossarm from slipping endwise relative to the support legs due to the normal stresses imposed on such a crossarm structure. In addition, the dowel pins also absorb some of the load in a direction normal to the crossarm which would otherwise be imposed entirely on the channel shaped retaining brackets. The dowel pins can be fitted within the respective recesses by either a friction fit, a slip fit, or a loose fit.

The channel shaped brackets which are used to secure the arcuate crossarm with respect to the support legs can be made of any suitable material such as reinforced plastic glass fibers, metal or other material. In order to secure the channel shaped retaining brackets to the crossarm, any suitable securing means can be used. For example, a plurality of bolts may be passed through the legs of the brackets as well as through the support legs to cooperate with suitable nuts. Alternatively, the brackets can be secured by pegs, for example, of nonmetallic material which are held in place by an adhesive. Such pegs can be made straight or with heads which abut the sidewalls of the bracket.

Alternatively, the joint between the arcuate crossarm and the support legs could also be made on a mechanical basis. Also, the space between the mating and abutting surfaces of the crossarm and support legs can be filled with an adhesive such as epoxy to increase strength of the joint therebetween or with a caulking compound to prevent water from seeping in to cause problems either by freezing or by introducing the deposits of contaminated material which could produce a non-desirable electrical conductive condition.

10 Instead of using an arcuate crosspiece, a horizontal crosspiece can also be utilized for mounting on the support arms in a symmetrical relationship about a vertical pole. However, where an arcuate crossarm is used, such can be formed into any arcuate or curvilinear shape suitable for use.

15 The crossarm assembly is installed at the top of the vertical pole such that the transmission lines and ground lines are clear of the vertical pole so that any interference by the vertical pole is avoided. Further, the conventional ground wire can be positioned on the crossarm in symmetrical relationship. In addition, the support legs can be secured to the pole, for example, by a bolt which passes through the center of the pole. Thus, the stresses and forces imposed on the vertical pole by the crossarm assembly are imposed substantially symmetrically on the pole without eccentricity.

20 25 These and other objects and advantages of the invention will become more apparent from the following detailed description and appended claims taken in conjunction with the accompanying drawings in which:

FIG. 1 illustrates a front view of the crossarm assembly according to the invention;

FIG. 2 illustrates a view taken on line 2—2 of FIG. 1;

FIG. 3 illustrates an exploded view of the crossarm, a support leg, dowel pin and retaining bracket;

35 FIG. 4 illustrates a modified securing means for securing the bracket to the support leg; and

FIG. 5 illustrates a further modification of the means for securing the bracket to the support leg.

40 Referring to FIG. 1, the crossarm assembly 10 is mounted on the upper end of a vertically disposed pole 11 symmetrically thereof by a pair of bolt assemblies 12. The crossarm assembly 10 is constructed of an arcuate crosspiece 13, a pair of support legs 14 which support the arcuate crosspiece 13 on the vertical pole 11, and securing means 15 which secure the arcuate crosspiece 13 to the support leg 14.

45 The arcuate crosspiece 13 is formed in any suitable shape, such as a curvilinear shape and is disposed in a concave up relationship to the pole 11. In addition, the crosspiece 13 is constructed of a solid rectangular cross section so as to be substantially uniform from end to end. This crosspiece 13 serves to support a plurality of electrically nonconductive conductor supports 16 thereon for suitable conductors 17 as are known.

50 55 Also, the crosspiece 13 serves to support any suitable ground wire (not shown) thereon in a symmetrical relationship to the pole 11. As shown, the conductor support 16 can be secured by the crosspiece 13 by any suitable bolt assembly 18 and can be symmetrically arranged along the crosspiece 13 relative to the pole 11 so as to avoid any eccentric loadings on the pole 11 and crossarm assembly 10. In order to provide an electrically nonconductive path between the conductors 17 and the pole 11, the crosspiece 13 is constructed of resin impregnated glass fibers in a known manner.

60 65 The support legs 14 are of solid rectangular cross section and are secured at one end by the bolt assemblies 12 to the vertical pole 11 while the opposite ends are secured by the securing means 15 to the crosspiece 13. As shown, the support legs 14 flare outwardly of the projected central line of the pole 11 so as to support the crosspiece 13 near the opposite ends thereof. In this case, the support legs 14 form a Y-shaped profile with the pole 11 for supporting the crosspiece 13. As above, the support legs 14 are also made of resin impregnated glass fiber material so as to present a nonconductive path.

70 75 Referring to FIGS. 1, 2 and 3, the securing means 15 includes a dowel pin 19 which is secured within mating recesses

20, 21 within the support legs 14 and crosspiece 13, respectively, a channel-shaped bracket 22 which passes around the crosspiece 13 and suitable bolt assemblies 23 which secure the bracket 22 to the support legs 14. Each dowel pin 19 is received in any suitable fashion within the recess 20 in the end of support leg 14. For example, the dowel pin 19 can be received with a frictional fit, slip fit or loose fit. The recesses 21 in the crosspiece 13 are similarly dimensioned to receive the dowel pin 19. The channel-shaped retaining bracket 22 is sized to pass over the crosspiece 13 and to extend downwardly along the side of each of the support legs 14. As shown, a pair of bolt assemblies 23 are used to secure the bracket 22 to each support leg 14.

The securing means 15 can be constructed of any suitable material. For example, the channel-shaped brackets 22 can be made of reinforced plastic glass fibers, metal or other materials, the dowel pin 19 can be made of similar material and the bolts 23 can be made of metal, plastic or glass fiber material.

Referring to FIGS. 1 and 3, in order to assemble the crossarm assembly 10 on a vertical pole 11, the support legs 14 are first secured to the pole 11 by the pair of bolt assemblies 12 as is known. Thereafter, the dowel pins 19 are inserted into the respective recesses 20 in the ends of the support legs 14 and the arcuate crosspiece 13 is inserted over these dowel pins 19. The dowel pins 19 serve to restrain the crosspiece 13 against endwise movement relative to the support legs 14. Next, the retaining bracket 22 is slipped over the crosspiece 13 and disposed over suitable bores 24 passing through the support legs 14 to receive the bolt assemblies 23. A pair of bolt assemblies 23 are then passed through the legs of the brackets 22 and support legs 14 and secured in place. The bolt assemblies 18 and conductor supports 16 can then be mounted on the crosspiece 13.

Alternatively, the crossarm assembly 10 can be preassembled prior to mounting on the vertical pole 11. In this instance, the crosspiece 13 is secured to the support legs 14 by the dowel pins 19 and retaining brackets 22 in similar manner to the above before mounting on the pole 11. Thereafter, the entire assembly 10 can be lifted into place and aligned with the bores 25 passing through the pole 11 so that the bolts 12 can be passed through the support legs 14 and pole 11 to secure the crossarm assembly 10 in place.

Referring to FIG. 4, wherein like parts have been designated with like reference characters, the securing means 15' can utilize pegs 26 to secure the retaining bracket 22 to the support legs 14. These pegs 26 can be made of cylindrical cross sections to mate with a friction fit within the brackets 22 while passing through the support legs 14. In order to further insure retaining of the pegs 26 in place, a suitable adhesive can be used to bond the pegs 26 to the support leg 14 or brackets 22 or both. These pegs 26 can also be made of any suitable material such as plastics, glass fibers or metal.

Referring to FIG. 5, wherein like references have been utilized to indicate like parts as above, the securing means 15'' can also utilize pegs or pins having heads 28 to dispose against the ends of the bracket 22, that is, against the exterior surfaces of the bracket 22. As shown, four such pegs 27 are used with two passing through holes in the respective ends of the brackets 22 into the bores 24 of the support leg 14. As above, the pegs 27 can be fitted with a friction fit into the support leg 14 and or can be provided with an adhesive securing means.

The invention thus provides a crossarm assembly which can be easily and quickly mounted on a pole with a minimal effort and expense. In addition, the crossarm assembly permits the conductors to be supported to be arranged symmetrically with respect to the pole. In this way, eccentric loading of the pole 11 and crossarm assembly 10 can be avoided.

The invention also provides a crossarm assembly which can be constructed entirely of electrically nonconductive and non-corrosive materials such that the path between the respective conductors and the pole can be made as long as possible.

It is noted that the dowel pins which are used to secure the

crosspiece to the support legs of the crossarm assembly serve a dual function in that such not only position the crosspiece endwise with respect to the support legs but also serve to absorb forces imposed normally on the crosspiece. Further, the dowel pins can be sized so as to permit the crosspiece and support legs to abut each other along substantial portions thereof or can be dimensioned to support the crosspiece in a slightly elevated position from the ends of the support legs. In either case, a suitable caulking compound 29 can be packed into the spaces between the crosspiece and support legs in order to prevent any accumulation of water or other deposits therebetween which might produce a nondesirable electrical conductive condition. In addition, a suitable adhesive 30, such as an epoxy, can be used to strengthen the joint between the support legs and crosspiece.

It is further noted that while the crosspiece and support legs are shown in the drawings as being made of solid cross sections, any suitable cross-sectional shape can be used. In a similar fashion, any suitable securing means can be used to secure a crosspiece to a pair of support legs.

What is claimed is:

1. A crossarm assembly comprising an arcuate crossarm of electrically nonconductive material and curvilinear shape, a pair of support legs of electrically nonconductive material disposed near opposite ends of said arcuate crossarm, and means securing said support legs to said arcuate crossarm, said means including a dowel pin disposed in the end of each support leg and received within said crossarm for retaining said crossarm endwise relative to said support legs.
2. A crossarm assembly as set forth in claim 1, wherein said crossarm is made of resin impregnated glass fibers.
3. A crossarm assembly as set forth in claim 1 is disposed in a concave up position relative to said support legs.
4. A cross arm assembly as set forth in claim 1 wherein said means includes a retaining bracket secured to each said support leg and passing around said crossarm.
5. A cross arm assembly as set forth in claim 4 wherein each retaining bracket is of electrically nonconductive material.
6. A crossarm assembly as set forth in claim 1 wherein said crossarm and said support legs are of solid cross section.
7. A cross arm assembly as set forth in claim 6 wherein said crossarm and said support legs are of rectangular cross section.
8. A cross arm assembly as set forth in claim 1 wherein said crossarm is spaced from each of said support legs in an elevated position and which further includes a caulking compound in the space between said crossarm and support legs.
9. A crossarm assembly as set forth in claim 1 wherein said crossarm is supported in spaced relation to each said support leg in an elevated position and which further includes an adhesive further securing said crossarm to said support legs.
10. A crossarm assembly comprising a cross arm, a pair of support legs disposed near opposite ends of said cross arm, at least a pair of dowel pins, each dowel pin being received in one of said support legs and said cross arm to position said cross arm relative to said support legs, and means securing said crossarm to said support legs.
11. A crossarm assembly as set forth in claim 10 wherein said means includes at least one retaining bracket passing around said cross arm and second means securing said bracket to one of said support legs.
12. A crossarm assembly as set forth in claim 11 wherein said second means includes at least one bolt passing through the end of said bracket and said support leg.
13. A crossarm assembly as set forth in claim 11 wherein said second means includes at least one peg secured in said support arm and passing through at least one end of said bracket.
14. A crossarm assembly as set forth in claim 13 wherein said peg has a head disposed against said end of said bracket.
